THERMOSTAT

Austin H. Osgood, Portland, Oreg., assignor of
one-tenth to Laurence Selling, Portland,
Oreg.

Application September 25, 1931
Serial No. 565,115

2 Claims. (Cl. 200—139)

This invention relates generally to thermostats, and particularly to the type employing bimetallic thermostatic elements.

The main object of this invention is to provide an exceedingly simple and efficient form of thermostat which will have a rapid make and break action capable of eliminating objectionable arcing and rendering possible the use of this thermostat in ordinary lighting circuits without the use of relays or other protecting devices.

These, and other objects, will become more apparent from the specification following as illustrated in the accompanying drawing, in which:

15 Fig. 1 is a plan of the thermostat with the case broken away in section.

Fig. 2 is a vertical section taken along the line 2—2 in Fig. 1 showing the parts in a circuit-closing position.

20 Fig. 3 is a side elevation showing the parts in a circuit-opening position.

Fig. 4 is a section taken along the line 4—4 in Fig. 1.

Similar numbers of reference refer to similar parts throughout the several views.

Referring in detail to the drawings, in order to illustrate the invention in its simplest form there is shown a moulded base 10 on the upper side of which is secured a flat spring 11 by means 30 of the screws 12 which are fastened to the insert 13, which is preferably moulded in the base 10. To the spring 11 is attached the bimetallic element 14 which is curled backwardly upon itself and its outermost portion 15 has secured thereto 35 at an intermediate point a soft iron armature 16. Near the end 17 is positioned a contact point 18 adapted to engage the post 19 when the end 17 is moved sufficiently toward the base 10. The binding post 20 is connected to the post 19 and 40 the binding post 21 is connected to the element 14 through the insert 13. In the base 10 is placed a threaded bushing 22 in which is a set screw 23 whose point bears against the rivet 24 which connects the bimetallic element 14 to the 45 spring 11.

With the exception of the armature 16 and the spring 11 the mechanism thus far described is quite similar to those now in common use.

Referring particularly to my invention same 50 will be seen to consist in the inclusion of a horseshoe magnet 25 whose poles 26 are placed between the armature 16 and the base 10, against which post the magnet 25 is held by the screws 27, or in any other convenient manner.

55 It must be understood that while a magnet of

the horseshoe type is referred to that any other form of permanent or electro magnet may be employed without departing from the spirit of this invention.

The operation of the device is as follows: The 60 thermostat is placed in a control circuit by merely attaching the ends of the wires 28 and 29 to the binding posts 20 and 21 respectively, and the instrument is positioned, of course, near the point at which the temperature is to be 65 controlled. It can readily be seen that a drop in temperature which will cause the element 14 to move toward the magnet 25 and eventually close the circuit through the point 18 and the post 19, will also cause the armature 16 to 70 approach the poles 26 of the magnet 25.

While the movement of the end 17 of the element 14, occasioned by changes in temperature, is somewhat slow it can be seen that the armature 16 enters the field of the magnet 25 the 75 pull of the magnet increases rapidly as the space between its pull and the armature decreases, so that the closing action is made very abrupt. Likewise when the temperature rises and causes the element 14 to bend away from 80 the post 19, the first portion of this tendency is to overcome by the holding action of the armature 16, storing up an initial tension in the spring of the element 14 which, when it exceeds the pull of the magnet, causes an extremely rapid separation of its contact points 18 and post 19, in either case eliminating entirely a tendency to arc at ordinary lighting voltages, thereby eliminating the so-called 85 stuttering action common in thermostats relying 90 entirely upon the heat changes for the making and breaking of a circuit.

It is obvious that the tension of the spring 11 and the spacing of the points 18 and post 19 may be regulated by means of the screw 23, 95 or the spacing of the points 18 and the post 19 may be varied by inserting or removing one or more washers 30 under the post 19, or between the armature 16 and the portion 15 of the bimetallic element 14.

100 It will be seen that the function of the magnet is to produce a rapid closing movement by a pull on the armature 16 just before the closing action has been completed by the bimetallic element 14, and to retard the opening action 105 after the time when it would have normally opened under the action of the bimetallic element 14. In other words, the circuit is closed under the action of the magnet and opened under the action of the spring, and the bi- 110

metallic element merely moves the parts into the control of the magnet or out of control of the magnet 25 and into control of the spring 11.

I am aware that many forms of thermostatic devices have been constructed in the past; it is therefore not my intention to cover such devices broadly, but I do intend to cover all such forms and modifications thereof as fall fairly within the appended claims.

10 I claim:

1. A thermostat having an insulating base, a spring having one end mounted on said base, a bi-metallic element mounted on the free end

of said spring, a contact post mounted on said base in the bath of movement of said bi-metallic element, an armature secured to said bi-metallic element between said post and spring, a horse shoe magnet secured against said base and having its poles in the path of said armature, and a screw for adjusting the tension of said spring.

2. The substance of claim 1, and means for adjusting the gap between the end of said bi-metallic element and said contact post.

AUSTIN H. OSGOOD.
